UNITED STATES PATENT OFFICE.

EDWARD D. FLINT, OF OAKLAND, CALIFORNIA.

DESIGN FOR A HORSESHOE-PAD.

SPECIFICATION forming part of Design No. 30,274, dated February 28, 1899.

Application filed February 6, 1899. Serial No. 704,743. Term of patent 14 years.

To all whom it may concern:

Be it known that I, EDWARD D. FLINT, a citizen of the United States, residing in Oakland, county of Alameda, State of California, 5 have invented and produced a new and original Design for a Horseshoe-Pad, of which the following is a specification, reference being had to the accompanying drawings, forming a part thereof.

10 Figure 1 is a view of the lower side of the pad. Fig. 2 is a view of the upper side.

My design comprises a segmental plate having the front approximately semicircular and the sides continuing in convergent curves 15 from a larger radius than the front portion, and at the termination these sides merge into a transverse and concaved rear outline. The front semicircular portion has an approximately level surface A, curving downwardly 20 into a thickened rear portion B, said rear portion having semiglobular indentations C made in its surface. A heart-shaped open-

ing D is made through the level front portion. The opposite or upper side of the pad has a triangular indentation E divergent from a 25 point near the heart-shaped opening to near the rear end of the pad, and a rib F, having the same curvature as the rear of the pad, extends across the rear of the triangular opening, said rib having its upper edge essentially level with the upper surface of the pad exterior to the triangular depression. 30

Having thus described my invention, what I claim as new, and desire to secure by Letters Patent, is—

35 The design for a horseshoe-pad or similar article substantially as shown and described.

In witness whereof I have hereunto set my hand.

EDWARD D. FLINT.
